LLC; Michael J. Bootcheck(57) **CLAIM**

The ornamental design for a PURSE as shown and described.

DESCRIPTION

FIG. 1 is a perspective view of a PURSE;

FIG. 2 is a front view thereof;

FIG. 3 is a rear view thereof;

FIG. 4 is a first side view thereof;

FIG. 5 is a second side view thereof;

FIG. 6 is top view thereof;

FIG. 7 is a bottom view thereof; and

FIG. 8 is a view in which the purse is opened to show an
interior of the PURSE.

The broken lines on claimed surfaces indicated by surface shading depict stitching and form no part of the claim. The broken lines surrounding portions without any surface shading depict portions of the article and form no part of the claim. The unshaded portions within these broken lines form no part of the claim.
